UNITED STATES PATENT OFFICE.

GUSTAV OTTO, OF HOBOKEN, NEW JERSEY.

DESIGN FOR A WINE-GLASS.

SPECIFICATION forming part of Design No. 15,058, dated June 10, 1884.

Application filed March 22, 1884. Term of patent 3½ years.

To all whom it may concern:

Be it known that I, GUSTAV OTTO, a citizen of the United States, residing at Hoboken, in the county of Hudson and State of New Jersey, have invented and produced a new and original Design for a Wine-Glass, of which the following is a specification, reference being had to the accompanying drawing, forming part thereof.

10 In said drawing the figure represents a side elevation of my newly-designed wine-glass.

The leading feature of my design consists in an ornamental broad base on the bottom of a slightly-tapering body.

15 In the drawing, A represents the body of the glass, of slightly-tapering form. To said body is attached the base B, which is wide at the bottom, and of corrugated or wavy form. A bead, b, made in imitation of a rope, is

shown next to the bottom of the body of the 20 glass. The base gives a handsome appearance to the glass.

I claim—

1. The design for a wine-glass herein shown and described, the same consisting of the body 25 A and the base B, corrugated as shown, and provided with a bead, b.

2. The design for a wine-glass herein shown and described, the same consisting of the body A, of tapering form, and the base B, provided 30 with annular corrugations and a bead, b, in imitation of a rope, as specified.

In testimony whereof I affix my signature in presence of two witnesses.

GUSTAV OTTO.
